UNITED STATES PATENT OFFICE.

WILLIAM E. LOTT, OF MINEOLA, TEXAS.

LATCH.

SPECIFICATION forming part of Letters Patent No. 629,166, dated July 18, 1899.

Application filed November 19, 1898. Serial No. 696,901. (No model.)

To all whom it may concern:

Be it known that I, WILLIAM E. LOTT, a citizen of the United States of America, residing at Mineola, in the county of Wood and State of Texas, have invented certain new and useful Improvements in Latches, of which the following is a specification, reference being had therein to the accompanying drawings.

This invention relates to improvements in latches, and particularly to that class known as "gravity-latches" for use on sliding or swinging gates or doors.

The object of this invention is to provide a novel combination whereby the latch is so pivoted as to prevent accidental displacement or disengagement by reason of the movement of the door or gate by reason of the agitation due to the wind, &c., or by reason of the swinging and swaying of a car in its travel.

The further object of the invention is the provision of a novel engaging member in conjunction with which the latch operates to accomplish the result.

Finally the object of the invention is to provide a latch which will be strong, durable, and efficient, as well as comparatively inexpensive.

With the above and other objects in view the invention consists in the novel details of construction, as well as in the arrangement and combination of parts, to be hereinafter more fully set forth and specifically set forth in the annexed claims.

In describing the invention in detail reference will be had to the accompanying drawings, forming part of this invention, wherein like characters of reference denote corresponding parts in the several views, and in which—

Figure 1 is a view in perspective of a latch and its engaging member applied to a swinging door. Fig. 2 is a view in elevation of a latch and its engaging member applied to a sliding car-door. Fig. 3 is a view in perspective of a modified form of the engaging member for the sliding door. Fig. 4 is a view in elevation of the car-door latch, with the latch proper shown in dotted lines in an elevated position to illustrate the provision made for attaching the ordinary car-seal.

In the drawings, 1 denotes a swinging gate,

and 2 the gate-post or stationary portion of the inclosure.

3 is a base-plate, and 4 an integral arm slotted longitudinally to receive the latch 5, 55 which is pivoted at one of its angles to the said arm. The inclined edge 6 of the latch is adapted to ride over its engaging member and in so riding to cam the latch upward until the said latch has passed the engaging member, when it will fall by gravity and confine the engaging member between the base-plate and the edge 7 of the latch. As the edge 7 is at right angles to the arm and as the pivotal point of the latch is above the point at 65 which the engaging member will abut the edge 7, any pressure exerted on the edge 7 of the latch will tend to give a downward pressure on the latch, thus holding the said latch against upward displacement, while the descent of the latch beyond a predetermined position is prevented by the flanges 8, extending from the upper edge of the latch, which engage the upper edge of the arm, whereby the latch is supported. An end flange 9 is 75 also formed on the latch and abuts the end of the arm to limit the upward swing of the latch, the said arm having its upper edge at the end rounded to admit a free swinging movement of the said latch. 80

The engaging member for the latch applicable to swinging doors or gates consists of a plate 10, having a lug 11 at right angles to the plate, the said latch being so positioned as to ride over the lug, as will be understood. 85

The latch for the sliding door is the same as that heretofore described; but the arrangement of the arm *a* is somewhat different in that the said arm is arranged longitudinally of the base-plate and extends outward from 90 the side thereof. The latch in this arrangement is provided with an offset 12, apertured to register with an aperture in the arm for the reception of the usual car-seal that the latch may not be raised without disturbing 95 the seal. The engaging member of this construction consists of a base-plate 13, having a top flange 14 at the front end, said flange terminating in a handle 15 at the rear. The top flange is provided with an elongated opening 100 16 to receive the latch, as will be understood, and this combination makes a strong fasten-

ing which will withstand the wear and rough usage to which the railway-car is subjected. As the flanged end of the plate of the engaging member protrudes beyond the edge of the door in order to engage the latch and as such protruding section might interfere with the free use of the opening in the car, I have arranged it in sections, the outer section being pivoted on the bolt 17, that the outer end 10 may swing upward out of operative position, while a downward pressure on the end will bring it into operative position, with the body and flange registering, and as the pivotal point is at the tip and the body and flange 15 register the extension is firmly held and the latch can ride thereover, since said latch will exert a downward pressure and no inconvenience will result, while the advantages of such an arrangement will be appreciated.

20 The construction and operation will, it is thought, be understood from the foregoing description, it being noted that various changes in the proportions and other details of construction may be resorted to without departing 25 from the spirit of the invention.

Having thus fully described my invention, what I claim as new, and desire to secure by Letters Patent, is—

1. In combination a latch-arm having a 30 rounded upper outer edge, and a slot, a latch pivoted near the end and depending through the slot, an end flange protruding over the upper outer edge, side flanges formed with the latch, and an engaging member for the latch, substantially as described.

35 2. In combination a latch-arm having a rounded upper outer edge, and a slot, a latch pivoted near the end and depending through the slot, an end flange protruding above the

upper outer edge, side flanges formed with 40 the latch and an engaging member for the latch consisting of a plate having a handle extending longitudinally thereof and terminating in a slotted extension to receive the latch, substantially as described. 45

3. In combination, a base-plate, a slotted arm having a rounded edge at the end, a latch pivoted in the slot of the arm, said latch having side flanges and a protruding end extending above the rounded edge at the end as set 50 forth, an engaging member consisting of a plate and a flanged extension, said extension being slotted to receive the latch, substantially as described.

4. In combination, a base-plate, a slotted 55 arm having a rounded edge at the end, a latch pivoted in the slot of the arm, said latch having side flanges and a protruding end as set forth, an engaging member consisting of a plate and a flanged extension, said extension 60 being pivoted to the plate to have an upward swing and being slotted to receive the latch, substantially as described.

5. In combination, a base-plate, a slotted arm having a rounded edge at the end, a latch 65 pivoted in the slot of the arm, said latch having side flanges and a protruding end as set forth, an engaging member consisting of a base and its extension pivoted thereto, a flange formed with the extension and extending back over the plate and terminating in a handle, substantially as described. 70

In testimony whereof I affix my signature in the presence of two witnesses.

WILLIAM E. LOTT.
